ROLL GRINDING MACHINE

Carl G. Flygare, Worcester, Mass., assignor to
Norton Company, Worcester, Mass., a corpora-
tion of Massachusetts

Application July 12, 1940, Serial No. 345,187

6 Claims. (Cl. 51—95)

The invention relates to grinding machines, and more particularly to a polishing attachment for finishing crowned rolls after a roll grinding operation.

One object of the invention is to make a simple and thoroughly practical finishing or polishing attachment for a roll grinding machine. A further object of the invention is to provide a polishing attachment for a roll grinding machine in which the polishing element is arranged so that it may readily follow the crown on the roll to be polished to produce a uniform polished surface thereon.

A further object of the invention is to provide a polishing attachment for a roll grinding machine which is adjustably mounted on the grinding wheel slide so that it may be rocked toward and from the work axis by a crowning mechanism uniformly to finish the periphery of a crowned roll.

A further object of the invention is to provide a roll polishing attachment in which the grinding wheel slide is rocked toward and from the axis of the work during the longitudinal reciprocation therebetween and to provide a pivotal support for a non-rotatable polishing element whereby it may readily follow the surface of the roll to be polished to produce a uniformly refined surface over the entire face of the crowned roll. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawings, in which is shown one of various possible embodiments of the mechanical features of this invention,

Fig. 1 is a front elevation of a roll grinding machine embodying this invention;

Fig. 2 is a cross-sectional view through the grinding machine, showing the polishing or finishing attachment in operative position;

Fig. 3 is a left-hand end elevation of the roll polishing attachment, on an enlarged scale;

Fig. 4 is a sectional view, taken approximately on the line 4—4 of Fig. 3;

Fig. 5 is a fragmentary sectional view, taken approximately on the line 5—5 of Fig. 3, showing the mounting for the roll finishing attachment; and

Fig. 6 is a fragmentary sectional view, on an

enlarged scale, showing the hand traverse mechanism for the table.

A roll grinding machine has been illustrated in the drawings comprising a base 10 which supports a longitudinally reciprocable table 11 on the usual flat way 12 and V-way 13. The longitudinally reciprocable table 11 is provided with a rotatable work support comprising a motor driven headstock 16 and a footstock 17. The headstock 16 and footstock 17 are provided with work supporting centers 18 and 19, respectively, which are arranged rotatably to support a roll 20 to be ground and finished. The roll 20 may be mounted on the centers 18 and 19, as is common practice in the art, or if the roll is very massive in size, it may be mounted in journal rests (not shown), as shown in the prior U. S. Patent to Norton No. 1,096,188 dated May 12, 1914, to which reference may be had for details of the support for the work not contained herein.

A rotatable grinding wheel spindle 21 is rotatably supported in a wheel head 22. The wheel head 22 is connected by a pair of aligned studs or trunnions 23 arranged on opposite sides of the wheel head 22, and which are supported on a transversely movable wheel slide 24. The wheel slide 24 is arranged to slide transversely on the base 10 on a pair of spaced parallel slideways 25 (only one of which has been shown in Fig. 2). The wheel slide 24 is arranged to be moved transversely relative to the base 10 by means of a suitable wheel feeding mechanism. This mechanism may be of any well known type, such as, for example, that shown in the prior U. S. Patent to Norton No. 762,838 dated June 14, 1904. This mechanism may comprise a half nut 26 depending from the under side of the transversely movable wheel slide 24. The half nut 26 meshes with or mates with a rotatable feed screw 27 which is journaled in bearings (not shown) in the base 10. The front end of the feed screw 27 is provided with a gear 28 which meshes with a gear 29 mounted on the rear end of a rotatable shaft 30. The shaft 30 is rotatably supported in the base 10 and is provided at its front end with a gear 31 which meshes with a gear 32 mounted on a rotatable shaft 33, the other end of which supports a manually operable feed wheel 34. By rotation of the hand wheel 34, a rotary motion will be transmitted through the gears above described to rotate the cross feed screw 27 so as to cause an endwise movement of the nut 26 to feed the wheel slide 24 and the wheel head 22 either toward or from the work piece or roll 20. In the grinding of cylindrical rolls for a roll-

ing mill, it is frequently necessary to produce a roll which is not a true cylinder, having a peripheral surface which is formed either with a concave or convex crown, such as a deflection curve or otherwise according to the requirements of the rolling mill. In the machine as illustrated in the drawings, the form or crown on the roll 20 is produced by rocking the wheel head 22 about its supporting pivot 23 relative to the transversely movable intermediate slide 24 as 10 the roll 20 and the wheel head 22 are reciprocated longitudinally relative to each other.

The work supporting table 11 is reciprocated longitudinally relative to the base 10 and the wheel head 22 to traverse the roll 20 being finished past the operative face of an abrading element to be hereinafter described. The table 11 is provided with a depending rack bar 35 by which the table 11 may be traversed by a manual or a power traversing mechanism, such as that shown in the prior U. S. patent to Norton No. 762,838 dated June 14, 1904. This mechanism has not been shown in detail, since it is not considered to be part of the present invention. Reference may be had to the above-mentioned patent for 25 details of disclosure not contained herein.

A gear 36 meshes with the rack bar 35 (Fig. 6) and is mounted on a rotatable shaft 37. A gear 38 which is mounted on the outer end of the shaft 37 meshes with a gear 39 rotatably mounted on a shaft 40 which also supports a manually operable traverse wheel 41. By rotation of the traverse wheel 41, a rotary motion may be imparted to the gear 36 and through the rack 35 to traverse the work supporting table 11 longitudinally relative to the base 10.

The table 11 may be reciprocated longitudinally by a power operated mechanism, as shown in the prior patent above referred to. This mechanism may comprise a rotatable power driven shaft 42 which is driven by a multiple speed drive contained within a casing 43, details of which have not been shown in the present case, since they are not considered to be part of the present invention. For details of this mechanism, reference may be had to the above-mentioned prior patent. The rotatable shaft 42 is operatively connected through a clutch mechanism and a gear mechanism to impart a reciprocatory movement to the rack bar 35 and the table 11. This table driving mechanism has not been illustrated in detail, since it is not considered to be a part of the present invention. For details of disclosure not contained herein, reference may be had to the above prior patent to Norton.

In order to provide a predetermined rocking motion of the wheel spindle 21 to rock the abrading element toward and from the axis of the roll 20, it is desirable to provide a mechanism to time the rocking movement of the abrading element 60 with the longitudinal relative reciprocation between the abrading element and the roll 20 to be finished. This is preferably accomplished by means of the gear 46 which meshes with the table rack 35 so that when the table 11 is moved longitudinally, a rotary motion is imparted through the gear 46 to a shaft 47. The rear end of the shaft 47 is provided with a gear 50 which meshes with a gear 51 mounted on a rotatable shaft 52. The shaft 52 also carries a gear 53 which meshes with a gear 54 mounted on a rotatable shaft 55. The shaft 52 and the gears 51 and 53 carried thereby are supported by a swinging arm 56 which is rotatably supported on the shaft 47. This permits the gear 54 to be changed when de- 75

sired and the gear 53 to be swung into mesh with the gear 54 and locked in mesh therewith by means of a clamping screw 57 which passes through the arm 56 and is screw threaded into a portion of the base 10. The left-hand end of the shaft 55 is preferably formed as a splined shaft 60 which passes through a correspondingly shaped aperture in a worm 61 which is rotatably supported in a gear casing 62.

The casing 62 is rigidly fixed to the transversely movable wheel slide 24. The worm 61 meshes with a worm gear 63 mounted on a transverse shaft 64 which is journalled in suitable bearings in the gear casing 62. The shaft 64 supports a cam 65 which is arranged to engage a rotatable follower roller 66 which is supported on a stud 67. The stud 67 is rotatably supported in bearings in a bracket 68 which is rigidly fixed to the pivotally mounted wheel head 22. The gear casing 62 is provided with an upwardly projecting stop surface 78 which is arranged to be engaged by an adjustable screw 71 which is screw threaded into a bracket 12 passing through the rear end of the rocking wheel head 22. If it is desired to hold the wheel head 22 against a rocking motion, the screw 71 may be adjusted to raise the rear end of the wheel head 22 so that the follower roller 66 is raised from operative engagement with the cam 65, so that even though the cam 65 is rotated by the longitudinal movement of the work table 11, no rocking or oscillating movement will be imparted to rock the wheel head 22. This mechanism is illustrated in detail in my prior U. S. Patent No. 2,132,941 dated October 11, 1938, to which reference may be had for details of disclosure not contained herein.

The wheel spindle 21 may be normally rotated by means of an electric motor 80 mounted on the upper surface of the wheel head 22. The motor 80 is provided with a driving pulley 81 which is connected by means of V-belts 82 with a pulley 83 mounted on the end of the wheel spindle. If it is desired to grind the roll, a grinding wheel (not shown) may be mounted on the other end of the wheel spindle 21 in a manner similar to that shown in my prior U. S. Patent No. 2,132,941.

After the roll 20 has been ground to the required and predetermined extent, it is desirable to provide a suitable finishing or polishing mechanism for producing a highly refined or polished surface on the roll. This is preferably accomplished by the provision of a roll polishing or finishing attachment whereby a non-rotatable abrading element may be employed for the final finishing operation. A polishing attachment 90 is provided which is supported on a tapered end portion 91 of the wheel spindle 21 (which normally supports the grinding wheel) and is held in adjusted position thereon by means of a nut 92. The attachment 90 is provided with a rearwardly extending arm 94 (Fig. 3) which is provided with a clearance hole 95 through which passes a stud 96. The stud 96 is fixedly mounted on the side of the housing 97 formed integral with or fixedly mounted on the pivotally mounted wheel head 22. Opposed adjusting screws 97 and 98 are screw threaded through a portion of the arm 94 and are arranged to engage the stud 96 on diametrically opposite sides thereof. By manipulation of the screws 97 and 98, the attachment 90 may be adjusted to a slight angular extend and the attachment 90 may be locked so as to hold the spindle 21 against rotation during the polishing operation.

The forward end of the bracket 90 is yoke-

shaped comprising the spaced arms 100 and 101 which serve as supports for a pair of vertically arranged aligned studs 102 and 103, respectively. The studs 102 and 103 are preferably supported in anti-friction bearings 104 and 105, respectively, which are carried by the arms 100 and 101, respectively, of the bracket 90. The studs 102 and 103 serve as a support for a substantially U-shaped bracket 106 which in turn supports a normally stationary lapping or abrading element, such as a wheel 107. The wheel 107 (Fig. 4) is supported by a wheel center 108 having an integral flange at one end thereof. An adjustable flange 109 is threaded onto the other end of the wheel center 108 by means of which the wheel 107 may be clamped in position on the center 108. The substantially U-shaped bracket 106 is provided with two parallel sides 110 and 111 which are spaced from each other by a distance sufficient to provide for the wheel 107 and its center 108. A stud 112 passes through an aperture 113 in the side plate 111 and passes through a central aperture 114 in the wheel center 108 and through an aperture 115 in the side plate 110. A binder nut 116 is screw threaded onto a threaded portion 117 formed on the left-hand end of the stud 112 (Fig. 4) by means of which the wheel 107 may be locked in adjusted position. The apertures 113 and 115 formed in the side plates 111 and 110, respectively, are preferably formed as elongated slots (Fig. 3) to facilitate a transverse adjustment of the stud 112 and the polishing or abrading element 107.

It is desirable to provide a transverse adjustment for the abrading member 107 so that its operative face, namely, the line of contact between the abrasive element 107 and the crowned roll 20 to be finished will be aligned with the pivotal axis of the substantially U-shaped frame 106. To accomplish this result, a gauge rod 120 is slidably mounted to an aperture 121 in the stud 102. The gauge rod 120 is provided with a gauge surface 122 which is accurately aligned with the axes of the studs 102 and 103.

When setting up the polishing apparatus for a polishing operation, the attachment bracket 90 is placed in position on the tapered nose of the wheel spindle 21, the nut 93 is then tightened to lock the bracket 90 in fixed position relative to the spindle 21, and the adjusting screws 97 and 98 are adjusted to lock the bracket, thus preventing any rotary motion of the spindle 21. The gauge rod 120 is inserted in the aperture 121 into the position illustrated in Fig. 3. The nut 116 is then loosened and the abrading element, such as wheel 107, is moved toward the right until its peripheral surface contacts with the gauge surface 122, after which the nut 116 is again clamped to lock the abrading element 107 in its adjusted position with its operative face or line of contact between it and the roll 20 to be polished in alignment with the axes of the studs 102 and 103, respectively. The gauge rod 120 is then removed and the polishing operation may proceed.

By aligning the operative surface of the abrading element 107 in alignment with the axes of the studs 102 and 103, the substantially U-shaped frame 106 will readily swing within its supporting anti-friction bearings 104 and 105, respectively, as the roll 20 and lapping element 107 are traversed longitudinally relative to each other so that the operative face of the abrading element 107 will follow the crowned contour of the roll 20 to be polished, thus producing a uniform

abrading motion over the entire width of the element 107.

The operation of this improved roll finishing apparatus will be readily apparent from the foregoing disclosure. A roll 20 to be ground and finished is placed in supporting engagement on the work supporting centers 18 and 19, respectively, after which the peripheral surface of the roll may be first ground, if desired, and then lapped or finished to the desired extent. After the grinding operation has been completed, the grinding wheel is removed and the bracket 90 placed in supporting position on the wheel spindle 21 and clamped thereon by means of the nut 93 and the bracket 90 is then clamped against oscillation by adjustment of the opposed adjusting screws 97 and 98.

The gauge rod 120 is then placed in operative position and the abrading element 107 is adjusted transversely until its operative face engages the gauge surface 122, after which the nut 116 is clamped to lock the abrasive element in adjusted position. The gauge rod 120 is then removed. The wheel slide 24 may then be adjusted transversely to move the abrading element 107 into operative contact with the periphery of the roll 20. The reciprocation of the table 11 may then be started to traverse the roll longitudinally relative to the abrading element 107. During the longitudinal movement of the table 11, a rocking movement is imparted to the wheel head 22 to rock the abrasive finishing wheel 107 transversely toward and from the axis of the roll 20 so that it will accurately follow the desired and predetermined contour during the finishing operation. At the same time, the frame 106 is free to swing about its supporting bearings 104 and 105, respectively, so that the peripheral surface of the wheel 107 will uniformly engage the surface of the roll 20 during its entire longitudinal reciprocatory stroke. The roll 20 may thus be lapped to present a highly refined lapped or polished surface thereon.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim:

1. In a roll grinding machine having a base, a longitudinally reciprocable work table, a rotatable work support on said table, a transversely movable slide, a lapping attachment adjustably supported on said slide, a pivotally mounted frame on said attachment which is pivoted on an axis at substantially right angles to the axis of the work support, a normally stationary lapping element adjustably mounted on said frame, means to traverse said table longitudinally, and a crowning mechanism which is actuated by and in timed relation with the longitudinal traversing movement of the table to rock said wheel head so as to maintain said lapping element in uniform engagement with the crowned surface of the roll being lapped.

2. In a roll grinding machine having a base, a longitudinally reciprocable work table, a rotatable work support on said table, a transversely

movable slide, a wheel head pivotally mounted on said slide, a rotatable wheel spindle on said head, and a roll lapping attachment comprising a frame adapted to be supported by said spindle, a yoke-shaped end on said frame, a substantially U-shaped frame, pivotal connections between the yoke and said U-shaped frame, the axis of said pivot being at substantially right angles to the axis of said spindle, a lapping element on said frame, and means to adjust said lapping element relative to said frame in a direction normal to the spindle axis so that the operative face of the lapping element may be aligned with the pivotal axis of said frame.

3. In a cylindrical grinding machine having a rotatable wheel spindle, a lapping attachment comprising a frame adapted to be mounted on said wheel spindle, means to hold said frame and spindle against rotation, a lapping element holder supported by said frame, pivotal connection between said frame and holder, the axis of the pivotal connections being at right angles to the axis of said spindle, and a non-rotatable lapping element on said holder.

4. In a cylindrical grinding machine having a rotatable wheel spindle, a roll lapping attachment therefor having a frame adapted to be supported on said spindle, means to clamp said frame and spindle against rotation, a lapping element holder supported by said frame, pivotal connections between said frame and said holder, and a non-rotatable lapping element on said

holder having its operative face aligned with the axis of said pivotal connections.

5. In a cylindrical grinding machine having a rotatable wheel spindle, a lapping attachment therefor having a frame adapted to be mounted on the wheel spindle, means to clamp said frame and spindle against rotation, a lapping element holder supported on said frame, pivotal connections between said frame and holder, the axis of said pivotal connections being at substantially right angles to the axis of said spindle, a non-rotatable lapping element on said holder, and means to adjust said lapping element relative to said holder to align its operative face with the axis of said pivotal connection.

15 6. In a cylindrical grinding machine having a rotatable wheel spindle, a lapping attachment therefor having a frame adapted to be supported on the wheel spindle, means to hold the frame and spindle against rotation, a yoke-shaped end on said frame, a substantially U-shaped frame, pivotal connections between said yoke and said U-shaped frame, the axis of said pivotal connections being at substantially right angles to the axis of said spindle, a lapping element on said frame, and means including a gauge to facilitate adjustment of the lapping element relative to the U-shaped frame to align its operative face with the axis of said pivotal connections.

CARL G. FLYGARE.
